UNITED STATES PATENT OFFICE.

FRANCIS H. RICHARDS, OF HARTFORD, CONNECTICUT, ASSIGNOR TO THE KEMPSHALL MANUFACTURING COMPANY, OF ARLINGTON, NEW JERSEY, A CORPORATION OF NEW JERSEY.

PLAYING-BALL.

SPECIFICATION forming part of Letters Patent No. 727,198, dated May 5, 1903.

Application filed September 3, 1902. Serial No. 121,934. (No model.)

To all whom it may concern:

Be it known that I, FRANCIS H. RICHARDS, a citizen of the United States, residing at Hartford, in the county of Hartford and State of Connecticut, have invented certain new and useful Improvements in Playing-Balls, of which the following is a specification.

This invention relates to playing-balls, especially to those used in the game of golf; and its object is to provide at a low cost a ball possessing the triple qualities of "putting," "approach," and "long drive."

In the drawings forming part of this specification, Figure 1 illustrates a completed ball, partly broken away to disclose its construction; Fig. 2 shows one of the segments, and Fig. 3 is an enlarged fragment illustrating the adhesion of the layers when compressed together.

Similar characters designate like parts in all the figures.

I use a hard center piece A, such as celluloid, gutta-percha, metal, or compressed leather, upon which I apply in various directions a plurality of cups B, of fibrous material, such as hide or leather, superimposing one upon the other, as indicated in Fig. 1, so that the joints between the various cups will cross each other. These cups B are previously formed in various sizes to fit one upon the other when applied to the core C and are each coated with a strong adhesive c, such as glue. These are each subjected to a high degree of pressure with some heat, if preferred,

so as to compact them and produce a high degree of resilience in each cup. By this means most of the mobility normally existing within each cup is retained in the finished ball, and this mobility modifies the action which the ball would otherwise have. The cups of the core are compressed together, so that they will become united together, thereby forming a practically solid fibrous core. At the same time the adhesive of one cup layer uniting with that of another will form an adhesive layer between the fibrous layers. The layers of glue may be as thin or as thick as required to make balls for different purposes, the glue itself forming resilient layers between the leather layers. Upon the core thus formed is

compressed a suitable shell D, of plastic material, such as celluloid or gutta-percha, under heat and pressure, and the compression is maintained during the solidification and hardening of the shell. It will be seen that a ball built in this manner possesses a relatively dead quality for a putting blow, a local resiliency at the point where the blow is struck for the approach, and a general resilience throughout the ball for bringing out the maximum flying power when the ball is struck a quick sharp blow for a long drive. It will also be seen that this ball has the advantage of durability and efficiency and can be made of materials which can be obtained of proper qualities and at relatively low cost.

It will be observed that the adhesive with which the layers are coated will, during the process of compression under heat, cause them to partially consolidate or unite, thus forming a practically solid core.

Variations of construction as well as material may be resorted to within the scope of this invention.

Having described my invention, I claim—

1. A playing-ball having a core composed partially of alternate layers of glue and leather, and a shell of plastic material holding said core under compression.

2. A playing-ball having a core partially built up of cups of leather, and a shell of plastic material holding said core under compression.

3. A playing-ball having a core partially built up of cups of leather, and a shell of gutta-percha compressed on said core.

4. A playing-ball having a core partially built up of cups of leather; said cups being coated with an adhesive, and all consolidated together under heat and pressure, and a shell of gutta-percha compressed on said core.

5. A playing-ball having a core partially built up of cups of leather; said cups being partially saturated with an adhesive, said cups being united together under heat and pressure, and a shell of plastic material compressed on said core.

6. A playing-ball having a core built up of cups of leather; said cups being partially saturated with glue, and all united together un-

- der heat and compression, and a shell of gutta-percha compressed on said core.
7. A playing-ball having a hard center piece; cups of leather coated with an adhesive applied to said center piece to form the core, and a shell of gutta-percha holding said core under compression.
8. A playing-ball having a hard center piece; cups of leather partially saturated with glue and applied to said center piece, and a shell of plastic material compressed on said layers.
9. A playing-ball having a hard center piece; cups of leather partially saturated with glue applied miscellaneously to said center piece so that the various joints between the cups will be staggered, and a gutta-percha shell inclosing said cups.
10. A playing-ball comprising a fibrous center piece; cups of leather miscellaneously applied to said center piece to form the core; said cups being coated with glue and a shell of gutta-percha compressed on said core.
11. A playing-ball comprising a core comprising alternate layers of leather and adhesive material, and a shell of plastic material upon said core.
12. A playing-ball comprising a core comprising alternate layers of leather and glue, and a shell of plastic material upon said core.
13. A playing-ball comprising a core comprising alternate layers of leather and glue, and a shell of gutta-percha upon said core.
14. A playing-ball comprising a sphere built up of alternate layers of glue and compressed leather.
15. A playing-ball comprising a sphere built up of alternate layers of glue and compressed leather, each of said leather layers consisting of cups.
16. A playing-ball comprising a center piece, a layer thereon built up of cups of leather, said cups being coated with an adhesive, and a cover of plastic material.
17. A playing-ball comprising a center piece, a layer thereon built up of cups of leather, said cups being coated with an adhesive and held under compression, and a cover of plastic material.
18. A playing-ball comprising a plurality of layers of leather partially saturated with glue, and a cover of gutta-percha.
19. A playing-ball comprising alternate layers of glue and leather, and a cover.
20. A playing-ball comprising alternate layers of glue and leather under compression, and a cover of gutta-percha.
21. A playing-ball comprising alternate layers of glue and springy fibrous material under compression, and a cover of fibrous material.
